UNITED STATES PATENT OFFICE

104,437

DESIGN FOR A SHOWCASE OR SIMILAR ARTICLE

Orville Bulman, Grand Rapids, Mich., assignor to E. O. Bulman Manufacturing Co. Inc., Grand Rapids, Mich., a corporation of Michigan

Application March 15, 1937, Serial No. 68,170

Term of patent 7 years

To all whom it may concern:

Be it known that I, Orville Bulman, a citizen of the United States, residing at the city of Grand Rapids, in the county of Kent and State of Michigan, have invented a new, original, and ornamental Design for a Showcase or Similar Article, of which the following is a specification, reference being had to the accompanying drawing, forming a part thereof.

The figure is a perspective view of a showcase or similar article showing my new design. The opposite end of the showcase, not shown, is a duplicate of the end shown and the back is substantially plain and unornamented.

I claim:

The ornamental design for a showcase or similar article, as shown and described.

ORVILLE BULMAN.
